(57) **CLAIM**

The ornamental design for a headlamp for cap as shown and described.

DESCRIPTION

FIG. 1 is a front, right and top perspective view of a headlamp for cap, showing my design.

FIG. 2 is a front, right and top perspective view thereof.

FIG. 3 is a rear, left and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is a front, right and top perspective view of a second embodiment of a headlamp for cap.

FIG. 11 is a front, right and top perspective view of the second embodiment of the headlamp for cap of FIG. 10.

FIG. 12 is a rear, left and bottom perspective view of the second embodiment of the headlamp for cap of FIG. 10.

FIG. 13 is a front elevation view of the second embodiment of the headlamp for cap of FIG. 10.

FIG. 14 is a rear elevation view of the second embodiment of the headlamp for cap of FIG. 10.

FIG. 15 is a left side elevation view of the second embodiment of the headlamp for cap of FIG. 10.

FIG. 16 is a right side elevation view of the second embodiment of the headlamp for cap of FIG. 10.

FIG. 17 is a top plan elevation view of the second embodiment of the headlamp for cap of FIG. 10.

FIG. 18 is a bottom plan elevation view of the second embodiment of the headlamp for cap of FIG. 10.

FIG. 19 is a front, right and top perspective view of a third embodiment of a headlamp for cap.

FIG. 20 is a front, right and top perspective view of the third embodiment of the headlamp for cap of FIG. 19.

FIG. 21 is a front, left and bottom perspective view of the third embodiment of the headlamp for cap of FIG. 19.

FIG. 22 is a front elevation view of the third embodiment of the headlamp for cap of FIG. 19.

FIG. 23 is a rear elevation view of the third embodiment of the headlamp for cap of FIG. 19.

FIG. 24 is a left side elevation view of the third embodiment of the headlamp for cap of FIG. 19.

(Continued)

FIG. 25 is a right side elevation view of the third embodiment of the headlamp for cap of FIG. 19.

FIG. 26 is a top plan elevation view of the third embodiment of the headlamp for cap of FIG. 19.

FIG. 27 is a bottom plan elevation view of the third embodiment of the headlamp for cap of FIG. 19.

FIG. 28 is a front, right and top perspective view of a fourth embodiment of a headlamp for cap.

FIG. 29 is a front, right and top perspective view of the fourth embodiment of the headlamp for cap of FIG. 28.

FIG. 30 is a rear, left and bottom perspective view of the fourth embodiment of the headlamp for cap of FIG. 28.

FIG. 31 is a front elevation view of the fourth embodiment of the headlamp for cap of FIG. 28.

FIG. 32 is a rear elevation view of the fourth embodiment of the headlamp for cap of FIG. 28.

FIG. 33 is a left side elevation view of the fourth embodiment of the headlamp for cap of FIG. 28.

FIG. 34 is a right side elevation view of the fourth embodiment of the headlamp for cap of FIG. 28.

FIG. 35 is a top plan elevation view of the fourth embodiment of the headlamp for cap of FIG. 28; and,

FIG. 36 is a bottom plan elevation view of the fourth embodiment of the headlamp for cap of FIG. 28.

The dashed broken lines depict portions of the headlamp for cap that form no part of the claimed design.
